UNITED STATES PATENT OFFICE.

EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

FILLING-PARTING MECHANISM.

1,272,557.

Specification of Letters Patent. Patented July 16, 1918.

Application filed June 21, 1917. Serial No. 176,215.

To all whom it may concern:

Be it known that I, EDWARD S. STIMPSON, a citizen of the United States, and resident of Hopedale, county of Worcester, State of Massachusetts, have invented an Improvement in Filling - Parting Mechanism, of which the following description, in connection with the accompanying drawing, is a specification, like characters on the drawing representing like parts.

This invention relates to improvements in filling parting mechanism for automatic filling replenishing looms. In such looms means are usually provided for severing the filling end, which extends from the selvage of the cloth to the bobbin about to be discharged, close to the shuttle and for clamping the severed end and carrying the same into the temple thread cutter which lies adjacent the selvage of the cloth. Such thread or filling parting means are ordinarily carried by the shuttle feeler which upon call for transfer is advanced toward the lay as the latter comes forward upon its last beat before transfer.

When the shuttle is improperly positioned the shuttle feeler engages the side of the shuttle and is forced backwardly carrying the usual dog out of the path of the bunter upon the lay and thus avoiding transfer. When, however, the shuttle is properly boxed the shuttle feeler passes beyond the end of the shuttle and the filling parting and clamping devices are caused to receive, cut and clamp the filling end.

Upon movement of the lay in the opposite direction the shuttle feeler moves forward in an arcuate path and draws the filling end into the usual temple thread cutter. This mechanism is well known and is of the general character disclosed in the patent to Northrop and Stimpson granted Jan. 23, 1900, No. 641,792, and in the patent to Draper No. 683,423 granted Sept. 24, 1910.

Where, as sometimes occurs, the filling balloons or slackens at the time the parting device moves forward it sometimes falls below the end of the parting device and is not severed, in which case it is apt to be caught and carried back into the cloth making an imperfection therein.

The present invention has for its object the provision of a simplified and efficient

means carried by the parting device which is operable to pick up a slack end and guide the same into jaws of the thread parting and holding device, thus insuring the cutting of the filling end and the clamping of the same in the usual manner.

The invention is illustrated herein in connection with a usual type of thread parting device carried by the shuttle feeler but it will be understood that this invention may be applied to other mechanisms within the spirit and scope of the appended claims.

The novel features of the invention will be more fully described in the following specification and particularly pointed out in the claims.

In the drawings;

Figure 1 is a transverse sectional view of the end portion of an automatic filling replenishing loom showing the invention applied to a filling parting instrumentality carried by the usual shuttle feeler,

Fig. 2 is a detail plan view of the end portion of the shuttle feeler and filling cutting and clamping device with the present invention embodied therein,

Fig. 3 is a detail side elevation of the filling parting and clamping devices with the guiding means forming the present invention co-operating with the lay to guide the filling into the jaws of the parting and clamping device.

The mechanism of the loom which is illustrated herein is of the well known "Northrop" type comprising a frame 1 having a breast beam 2 upon which is mounted the hopper stand 3 which carries the usual rotary hopper or feeder, not shown, adapted successively to deliver filling carriers in the path of the transfferer 4 which is pivotally mounted upon a stud 5 carried by the hopper frame and actuated by the dog 6 when the latter is positioned in the path of the bunter 7 upon the lay 8 which is carried upon the usual swords 9.

The thread parting and clamping mechanisms are carried upon the usual shuttle feeler 10 which is pivotally and slidably mounted at its lower end upon a stud 11 projecting laterally from the arm 12 of a bracket 13. The shuttle feeler is actuated in the usual manner by an arm 14 rigidly connected to the controller rod 15 which is

oscillated by a moving actuator upon detection of failure of filling by a weft fork or feeler.

The thread cutting and clamping mechanism as illustrated herein comprises a member or plate 16 having laterally extending flanges or lugs 17 and 18 fixedly secured to the shuttle feeler 10 by a bolt 19 and a stud or rivet 20.

10 The lower portion of the rearward end of the member 16 has a wide web 21 which forms a support for the filling end and also serves as a ledger plate with which the filling clamping means coöperates. The outer 15 end of the member 16 is fork shaped to correspond substantially with the usual forked shaped end of the shuttle feeler. The cutting blade and the movable clamping member are preferably so connected as to move 20 in unison and are pivotally mounted upon the same shaft. As shown in the present drawing the cutter blade 22 lies between the member or plate 16 and the feeler 10 and is pivotally mounted upon the bolt 19. It co- 25 operates with a stationary ledger blade 23 which is secured to the face of the shuttle feeler 10 beneath the lower arm of its bifurcated end.

The movable clamping member comprises a metallic plate 24 and preferably a 30 fiber plate 25 of the same size and shape which are pivotally mounted upon the bolt 19. A spring 26 coiled about the stem of the bolt 19 and lying between its head and 35 the clamping plate 24 serves to force the clamping plate 24 yieldably against the member 16 so that it will coöperate properly with the ledger plate 21. The member or plate 16 is firmly forced against the cutting blade by a dished washer 27 which lies 40 between a shoulder upon the bolt and the inner face of the plate or member 16.

The movable cutting blade 22 and clamping members 24, 25 are rigidly secured together at their opposite ends by a pin 28 having a laterally extending stem operable 45 in a manner which will hereinafter be described to actuate these movable parts in such a manner as to open the cutting and 50 clamping mechanism.

The movable cutting blade is provided with a downwardly extending heel 29 adapted to be engaged by the lay when the filling parting device moves rearwardly and 55 meets the approaching lay. This heel desirably is reinforced by a block 30 of considerably greater thickness than the blade itself both for the purpose of strengthening the parts and for providing a sufficiently broad 60 engaging surface to prevent the cutting of the lay.

Upon backward movement of the shuttle feeler and the complementary forward movement of the lay the heel 29 comes into 65 engagement with the side of the lay and

moves the cutter 22 and the clamping members 24, 25 about the pivotal bolt 19 so that their ends respectively engage, cut and clamp the end of the filling at points quite close to the shuttle.

Upon the reverse movement of the lay and shuttle feeler the filling end thus cut and clamped is carried forward toward the breast beam and the filling drawn into position to be engaged by the usual temple 75 thread cutter not shown. It is to be noted that in the mechanism illustrated herein the cutter and clamp are normally in closed position. Any usual means may be employed to open the cutter and clamp as the 80 shuttle feeler moves to cutting position. A convenient mechanism which is illustrated herein comprises a switch cam 32 which is pivotally mounted upon a stud 33 at the end of an arm 34 forming an extension of 85 the arm 12 of the bracket 13, the switch cam 32 being normally held by a spring, not shown, surrounding the stud 33, in vertical position and prevented from forward movement toward the breast beam by suitable 90 means such as a lug in its path.

By this construction the switch cam engages the pin 28 upon the rearward movement of the shuttle feeler and depresses it so as to open the movable blades of the 95 clamp and cutter during the movement of the parting device to filling engaging position.

The tension of the springs 26 and 27 serves to hold the parting and clamping device open until the filling enters between the movable and stationary jaws thereof and until the lay striking against the heel 29 of the movable cutter closes said jaws to 100 cut and clamp the filling. Upon the forward movement of the shuttle feeler 10 the pin 28 pushes aside the switch cam 32 so that the clamp may remain closed until the 105 next rearward movement of the shuttle feeler.

The mechanism thus described is of a usual character and of well known operation to those familiar with looms. In this construction it is, of course, necessary that the shuttle feeler shall escape the top of the 110 lay as they approach each other, consequently there is a sufficient distance between them to permit a slack end to drop beneath the lower blade of the cutting and clamping mechanism. Thus the filling end 115 may fail to enter between the cutting and clamping jaws and consequently will not be cut so that after transfer takes place a loose end will remain which may be whipped into the cloth.

The present invention is designed to overcome this defect and comprises a yieldable member carried by the thread parting and clamping mechanisms which is adapted to engage the lay and passing beneath any 120

filling which may rest upon it, pick said filling up and guide it into the jaws of the parting and clamping mechanism.

A preferred instrumentality for thus 5 picking up the slack filling end comprises a spring wire 35 coiled about the bolt 19 and having one end 36 anchored in the flange 17 of the plate or member 16, while its other end is bent into substantially triangular 10 form, thus providing a downward and forward extension 37 and a forwardly extending portion 38. The wire 35 preferably lies in a slot extending longitudinally and substantially centrally of the ledger blade 21 15 preferably extending to the junction of the web or flange 18 therewith.

The wire 35 is so constructed and wound upon the bolt 19 that the triangular end normally lies in a position beneath the ledger 20 plate 21 as is illustrated in Fig. 1.

In order to insure the passage of the pick up 35 beneath any slackened filling which may lie upon or adjacent to the lay the race plate 39 of the lay is provided with a recess 25 40 along its forward edge to receive the pick up 35 and a portion of the race plate has a bevel 41 which serves as a cam to raise the pick-up and thereby cause it to guide the filling into the jaws of the thread parting 30 and clamping device.

This mechanism while very simple in construction is exceedingly efficient in operation and effectively guides a slackened filling into the jaws of the thread parting and clamping device. The smooth surface of 35 the wire member 35 readily enters beneath the filling and raises it so that the advancing jaws of the filling parting member pass over it. The angle of inclination of the 40 portion 37 of the pick up member may be and preferably is such as to cause said pick up member when in thread supporting position to incline downwardly toward the bases of the jaws of the parting and clamping 45 mechanism thereby still further tending to force the filling into the field of action of the jaws.

It will be understood that while the pick up instrumentality is described herein as 50 of wire it may be made of any suitable material and may be located in convenient position to perform the functions herein described.

Having thus described my invention what 55 I claim as new and desire to secure by Letters Patent is:

1. In a loom comprising a shuttle feeler, means upon said shuttle feeler to part and clamp the filling adjacent the shuttle including a stationary ledger plate, cutting and clamping members located respectively on opposite sides thereof and movable relatively thereto, means located intermediate

of said cutting and clamping members adapted to enter beneath the filling as the 65 lay beats up and to guide the filling into the clamping and guiding means.

2. In a loom comprising a shuttle feeler, means upon said shuttle feeler to part and clamp the filling adjacent the shuttle including a stationary ledger plate, cutting and clamping members located respectively on opposite sides thereof, means for simultaneously actuating said cutting and clamping members, means for picking up the filling comprising a yieldable member guided in a slot in said ledger plate intermediate of said cutting and clamping members adapted to pass beneath the filling upon the beat-up of the lay and means for raising 80 said yielding member to cause the filling to enter the cutting and clamping mechanism.

3. In a loom comprising a shuttle feeler, means upon said shuttle feeler to part and clamp the filling adjacent the shuttle including a stationary ledger plate, cutting and clamping members located respectively on opposite sides thereof and having a common pivotal connection, means operable by engagement with the lay upon its beat-up 85 simultaneously to oscillate said members, means for picking up the filling including a spring wire coiled upon the pivotal support of said cutting and clamping members and guided in a slot in said ledger plate 90 intermediate of said cutting and clamping plates, the end of said yieldable member being formed to engage said lay and to enter beneath the filling and means upon said lay for raising the end of said yieldable 95 member to cause the filling to enter the cutting and clamping means.

4. In a loom comprising a shuttle feeler, means upon said shuttle feeler to part and clamp the filling adjacent the shuttle including a stationary ledger plate and relatively movable cutting and clamping members located at opposite sides of said ledger plate, means operable by engagement of the lay to close said cutting and clamping means 105 and a yieldable member mounted in a slot in said ledger plate adapted to engage the lay and entering beneath the filling to guide the latter into the jaws of the cutting and clamping means.

5. In a loom comprising a shuttle feeler, means on said shuttle feeler to part the filling adjacent the shuttle, a spring wire pivotally connected to said parting means adapted to engage the lay, and a cam upon said lay for raising said wire to cause the same to direct the filling into the field of action of the parting means.

In testimony whereof, I have signed my name to this specification.

EDWARD S. STIMPSON.
